SUCTION CLEANER

Charles H. Taylor, Springfield, Mass., assignor to
The Hoover Company, North Canton, Ohio, a
corporation of Ohio

Application January 28, 1938, Serial No. 187,379

18 Claims. (Cl. 15—6)

The present invention relates to suction cleaners in general and particularly to new and novel improvements in suction cleaner agitating means. More specifically the invention comprises an improved rotary agitator in a suction cleaner in which proper and effective brushing is obtained regardless of the bristle length which varies with wear and the life of the brush.

It is an object of the invention to provide a new and improved rotary agitator for suction cleaners. It is another object of the invention to provide a new and improved suction cleaner agitator embodying rigid beating and flexible brushing means. Another object of the invention is to provide a rotary agitator embodying means of fixed radial extension and brushing means which are automatically adjusted to compensate for bristle wear. A still further object of the invention is to provide a rotary agitator for a suction cleaner embodying a large diameter cylindrical body formed with rigid beating elements and from which project brushing elements subject to decrease in length with wear, there being means to compensate for the latter. Another object is to provide a rotary agitator for a suction cleaner embodying rigid beating elements rotatable about a fixed axis and brushing elements rotatable about an axis which is adjustable to compensate for brush wear, the brushing and beating elements contacting the same part of the surface covering. Still another object of the invention is to provide a rotary agitator embodying brushing and beating elements, the brushing elements floating with relation to the surface covering undergoing cleaning to insure proper brushing action regardless of bristle length. These and other more important objects will appear upon reading the following specification and claims and upon considering in connection therewith the attached drawings.

Referring now to the drawings:

Figure 1 is a front elevation of a suction cleaner embodying the present invention, the nozzle wall being broken away to show the agitator positioned therein:

Figure 2 is a horizontal section upon the line 2—2 of Figure 1 and shows the agitator constructed in accordance with the present invention mounted for operation within the cleaner nozzle;

Figure 3 is a section through the agitator upon the line 3—3 of Figure 2 and discloses the helically extending brush elements and their rela-

tionship to the enclosing large diameter cylindrical body:

Figure 4 is a section upon the line 4—4 of Figure 2 and shows the driving gear keyed to the rotatable agitator body;

Figure 5 is a section upon the line 5—5 of Figure 2 and shows an end plate of the pivoted agitator-supporting frame and the spring means which secure the agitator in its seat with the frame located in the nozzle;

Figure 6 is a section upon the line 6—6 of Figure 2 and discloses a pair of the gears by which the rotatable brush is driven by the enclosing rotatable agitator body;

Figure 7 is a view in perspective of the stub shaft which supports one end of the rotatable agitator;

Figure 8 is a detail view of the stationary brush-supporting bracket, with stops, which is carried by the stub shaft of Figure 7;

Figure 9 is a hanger support by which the brush shaft is pivotally mounted upon the support bracket of Figure 8;

Figure 10 is a detail showing of the elements 25 of Figures 7, 8 and 9 operatively related and discloses the relative pivotal movement permitted the hanger support by the support bracket;

Figure 11 discloses somewhat diagrammatically the vertical adjustment permitted the rotatable brush.

The modern suction cleaner embodies air moving means and surface agitating means to accomplish effective cleaning. The agitating means preferably comprise a rotatable agitator 35 which includes rigid, positive beating elements and flexible brush elements. In cleaner operation the rotation of the agitator dislodges the imbedded foreign material from the surface covering and it is removed by the air stream drawn 40 by the air-moving means.

The rigid beating elements of the agitator are usually of metal and through the life of the machine are not subjected to change in size or relationship because of wear. The brush elements, however, are usually made of bristles and are very definitely subject to wear which decreases their length. With the rigid beating elements rotating at a fixed diameter about the axis of rotation, it is necessary for the flexible brush elements to extend to an equal distance from that axis or the entire surface contact is performed by the beating elements, the brushing elements rotating ineffectively. As the brush elements become shorter in length it becomes necessary either to replace them with new

brush elements or to provide means by which they can be adjusted to compensate for the wear. In the past agitators have been provided with manually adjustable brushes which can be removed and reinserted to new positions to compensate for decreased bristle length. Rotary brushes have also been made in which manual adjusting means effect greater or lesser brush extension. According to the present invention, however, there is automatic compensation for decrease in brush bristle length without attention from the user.

Referring again to the drawings and to Figures 1 and 2 in particular, a modern suction cleaner embodying the invention is disclosed. The cleaner body construction generally is of common and well known form and includes a nozzle casing 1 which supports a motor casing 2 housing an unshown motor. A fan chamber 3 is interiorly connected to the nozzle and contains a rotatable suction-creating fan 4 which is driven by the unshown motor. The extended lower end of the motor shaft 5 drives a power-transmitting belt 6 which seats upon a rotary agitator, indicated generally by the reference character 7, located within the nozzle 1. Agitator 7 is so positioned that it is adapted to contact a lifted surface covering between the front and rear nozzle lips 8 and 9, respectively. The cleaner body is movably supported upon wheels 10, 10 etc., and a handle 11 is suitably connected to enable the operator to propel the machine over a surface covering undergoing cleaning.

The agitator 7 comprises an elongated cylindrical body 13 upon the surface of which extend rigid beating elements 14, 14 and which is formed with a pulley surface 15 which seats the belt 6. End plates 16, 16 close the agitator ends and rotatably support the agitator upon stub-shafts 17, 17 by means of sleeve bearings 18, 18. The outer end of each stub-shaft 17 is secured in a thread guard member 20 which is itself non-rotatably supported in the nozzle in a manner to be hereinafter explained.

Within the body 13 is the brush 22 comprising an elongated small diameter hollow cylindrical body 23 from which extends a helically arranged row of bristle tufts 24, 24 etc. carried by tuft seats 25, 25 etc. The brush body 23 is normally substantially aligned with the stub-shafts 17, 17 and the bristle tufts 24, 24 extend radially outward through the helically arranged slots 27, 27 of body 13 which are present for that purpose. Brush body 23 is itself rotatably mounted on a non-rotating supporting shaft 29 by means of a sleeve bearing 30, the shaft, as well as the entire brush 22, being positioned entirely within the confines of the agitator body 13.

The means by which the brush 22 is supported within cylindrical body 13 for limited lateral displacement toward and from the surface covering undergoing cleaning comprises hanger brackets 34, 34 which seat non-rotatably upon the squared inner ends of the stub-shafts 17, 17. Each bracket is provided with an offset bearing seat 35 and with stop pins 36, 36. In position upon the stub-shaft 17 each bracket 34 is arranged with its bearing seat 35 positioned substantially in the same horizontal plane as the stub-shafts 17, 17 which results in the stops 36, 36 at each end of the agitator being one above and one below that plane.

Each outer reduced end of brush shaft 29 beyond the body 22 seats a support element 38 which is itself formed with a bearing seat 39. A

5 sleeve bearing 42 seats within bearing seats 38 and 39, as is clearly shown in Figure 2, the bracket 34 and the support 38 being adjacent with the shaft-carrying end of support 38 extending between stops 36, 36, as is clearly illustrated in Figure 10. A driven shaft 43 rotatably seats within each bearing 42 and together with it forms a pivotal mounting for a support 38 upon the bracket 34 by which the former can 10 move between an upper limit defined by an upper stop pin 36 and a lower limit defined by a lower stop pin. In substantially mid-position between these limits the brush shaft 29 is in exact alignment with the stub-shafts 17, 17 as is 15 clearly illustrated in Figures 2 and 10. The rigidity of the arms 38, 38 at the ends of the brush body and of the supporting means therefor is such that relative twisting movement between the ends of the brush body is entirely prevented, the shaft 29 remaining parallel at all times with the axis of rotation of the body 13, as defined by the stub-shaft 17, 17.

The driving means by which the brush 22 is rotated upon its pivoted supporting shaft 29 comprise gear trains which interconnect the cylindrical body 13 and the brush body 23 at both ends of the latter. A gear 46 seats upon the stub-shaft-carried bearing 18 inside the agitator end plate 16 and, in fact, extends between that end plate and the bearing in the embodiment shown for constructional purposes. Gear 46 rotates with end plate 16 being fixed thereto by the key 47.

Upon the extended end of shaft 43 carried by 35 bracket 34 is positioned a second gear 48 which meshes with gear 46 to rotate the shaft which, as above described, forms the pivotal axis for the laterally displaceable brush body 23. At the opposite end of shaft 43 a third gear 50 is provided which meshes with a fourth gear 51 rotatably mounted upon the brush shaft 29 by bearing sleeve 30 and which is pinned to that sleeve and to the brush body 22 by pin 52. The gear trains 46, 48, 50 and 51, there being one at each 40 end of the brush, positively connect the brush body 23 with the agitator cylindrical body 13 and rotary movement of one body is directly communicated to and results in rotation of the other body.

The entire agitator construction is removably supported within the cleaner nozzle by a pivoted frame 55 the forward member of which comprises the front nozzle lip 8 and each side plate member of which is formed with an upwardly opening slot 56 which receives and seats the axially extending seat abutment 57 formed upon the exterior face of the adjacent thread guard 20. A pivoted spring element 58, there being one carried by each frame end plate, extends across the slot 56 with its outer end underlying a nozzle-carried pin 59 which forces the spring 55 downwardly to lock the abutment 57 within the seat of the frame.

The frame 55 itself is pivoted upon pins 60, 60 at the rear of the rear nozzle lip 9 and is adapted to be pivoted up into the nozzle mouth or downwardly therefrom, manually operable retaining latch means 61 of the common and well known type being provided adjacent the front lip 8 to retain the frame in the upper position.

The operation of the cleaner constructed in accordance with the present invention begins upon the closing of the unshown motor switch which causes the cleaner motor to rotate thereby driving the suction-creating fan and rotating the

agitator 7. Suction created by the fan 4 effects a lifting of the surface covering below the nozzle upwardly into contact with the lips 8 and 9 and into contact with the rotating agitator 7 driven by belt 6. The rigid beating element 14 upon the surface of body 13 of agitator 7 beats the surface covering while the brush elements 24 brush the covering. The downwardly extended brush tufts 24 of the brush 22 at all times ride upon the lifted surface covering and project outwardly through the cylindrical body 13 just sufficiently to accomplish that result, there being sufficient penetration into the covering, of course, to provide sufficient resistance to support the brush 22. The brush rotates with the cylindrical body 7 being driven by the gear trains 46, 49, 50 and 51. If the bristles 24, 24 etc. of the brush 22 are relatively new and long the support 38 will be pivoted upon the pivot pin 43 so that it will extend closely adjacent the upper stop 36. As the brush tufts wear, however, the supports 38, 38 will gradually pivot downwardly until they eventually ride upon the lower stops 36, 36 at which time it becomes necessary to replace and renew the brush bristles.

When brush renewal finally does become necessary, or if for any other reason it becomes necessary to remove the agitator from the nozzle, the operator need only release the frame 55 by operating the latch 61. The agitator in its frame is thereupon removable downwardly through the nozzle mouth and thereafter the agitator can be removed from the frame by drawing the supporting abutment 57, 57 outwardly through the frame slots 56, 56, the locking springs 58, 58 pivoting upwardly and overcenter to permit that result. Upon the agitator being reconstructed or repaired it is again inserted into the frame 55, the spring lock 58 is again extended over the top of the abutment 57 at each end of the agitator and the frame is lifted upwardly into the nozzle. Springs 58, 58 are contacted by the pins 59, 59 and securely lock the agitator in the frame and the replacement is completed by the securing of the latch 61.

I claim:

1. A rotary agitator for a suction cleaner comprising a hollow cylindrical body, beater elements on said body, means to mount said body for rotation about its major axis, a brush in said body and projecting therefrom, non-rotating means mounting said brush for rotation about a non-rotating axis laterally displaceable in said body relative to said major axis, and means positively to rotate said brush about said laterally displaceable axis upon the rotation of said body.

2. In a suction cleaner, a rotatable agitator comprising a beater element rotatable about a fixed axis, a brush rotatable about its own independent axis only, which axis is positioned within the orbit described by said beater element, and means floatingly mounting said brush for vertical displacement independently of said element.

3. In a suction cleaner, a rotatable agitator comprising a beater element rotatable about a fixed axis, a brush rotatable about its own independent axis within the orbit described by said beater element, means floatingly mounting said brush for vertical displacement independently of said element, and power-transmitting means to rotate said brush upon the rotation of said element.

4. A rotary agitator for suction cleaners comprising a beater element, means to support rotatably said element, a brushing element rotatable about an axis within the orbit of said beater

element and subject to decrease in size upon wear and to decrease in its radial extension from its axis of rotation, means rotatably and adjustably mounting said brushing element to raise and lower its axis of rotation, and power-transmission means to rotate said brushing element upon rotation of said beater element.

5. In a suction cleaner, a nozzle, means to lift a surface covering undergoing cleaning into contact with the nozzle, a rotary agitator in said nozzle, said agitator including a body, beater elements on said body, means to support said body rotatably in fixed relationship to said nozzle, a rotary brush within said body and extended radially therethrough to be supported upon the lifted surface covering, means mounting said brush for vertical movement under a force received from said covering, and means to rotate said body and said brush.

6. In a suction cleaner rotatable agitator, a rotatable beater element, a rotatable brush element, means to support said beater element for rotation about a fixed axis, and adjustable means to support said brush element for rotation about an axis movable relative to said fixed axis, into coincidence therewith, and radially toward and from said fixed axis on both sides thereof.

7. In a rotary agitator for a suction cleaner, a beater element, means to support said beater element for rotation about a fixed axis, an agitating element subject to wear, means supporting said agitating element for rotation about a movable floating axis about which the agitating element in rotation describes an orbit which is tangent to the orbit described by said beater element only at the point of contact with a surface covering which is at all times directly below said fixed axis.

8. In a rotary agitator for a suction cleaner, a beater element, supporting means mounting said beater element for rotation about an axis, a brush element, stationary non-rotating means adjustable relative to said first-mentioned means supporting said brush for rotation about an axis vertically movable in a path substantially including said fixed axis, characterized in that in operation the vertical position of said brush element axis is determined by the contact of the brush element with a surface covering undergoing cleaning.

9. A rotary agitator for suction cleaners comprising a rotatable cylindrical body, beater elements on said body, stationary end members to support rotatably said body, a brush shaft within said body mounted upon said stationary end member for vertical displacement, and a rotatable brush on said shaft and extended through said body.

10. A rotary agitator for suction cleaners comprising a rotatable hollow body, a beater element on said body, stationary members to support rotatably said body, a brush within said body supported on said stationary member for movement toward and from a surface undergoing cleaning and extended radially beyond said body, and means to rotate said brush upon the rotation of said body.

11. A rotary agitator for suction cleaners comprising a hollow body, beater elements on said body, a stationary member at the end of said body, a fixed stub-shaft on said stationary member rotatably supporting said body, a brush within said body extended radially therebeyond, and means including said shaft pivotally mounting said brush for free movement in an arc in a ver-

tical plane, and means to rotate said brush upon the rotation of said body.

12. A rotary agitator for suction cleaners comprising a hollow body, beater elements on said body, a stationary member at the end of said body, a fixed stub-shaft on said stationary member rotatably supporting said body, a gear on said shaft rotatable with said body, a driven shaft carried by said stub-shaft within said body at one side thereof, gears on the opposite ends of said driven shaft, one of said gears meshing with said first-mentioned gear to cause said shaft to rotate upon rotation of said body, a brush within said body extended radially therebeyond, means pivotally supporting said brush upon said driven shaft for vertical displacement, and a gear connected to said brush in mesh with a gear on said driven shaft to rotate said brush upon rotation of said body.

13. A rotary agitator for suction cleaners comprising a hollow body, beater elements on said body, a stationary member at the end of said body, a fixed stub-shaft on said stationary member rotatably supporting said body, a gear on said shaft rotatable with said body, a driven shaft carried by said stub-shaft within said body at one side thereof, gears on the opposite ends of said driven shaft, one of said gears meshing with said first-mentioned gear to cause said shaft to rotate upon rotation of said body, a brush within said body extended radially therebeyond, means pivotally supporting said brush upon said driven shaft for vertical displacement, a gear connected to said brush in mesh with a gear on said driven shaft to rotate said brush upon rotation of said body, said brush being adapted to ride upon the surface covering undergoing cleaning, and means to limit the range of pivotal movement of said brush.

14. In an unitary rotary agitator for a suction cleaner, a rotatable body, means rotatably supporting said body, rigid beating means carried by said body, flexible brushing means rotatable with said beating means, and movable within limits relative thereto, and non-rotating means mounting said brushing means for vertical movement independent of said rigid beating means and to-

ward the underside of said body and from a surface undergoing cleaning in the rotation of said body.

15. In a suction cleaner, a casing, an agitator body, means rotatably supporting said agitator body on said casing, rigid beating means mounted on said body for rotation in a fixed orbit, flexible brushing means, means supporting said brushing means in said body for independent rotation about its own separate axis, said supporting means including a fixed support and relatively movable parts adjustable in agitator operation by surface-exerted force transmitted thereto by said brushing means, and means to rotate said brushing means about its own axis upon rotation of said body.

16. In a rotary agitator for a suction cleaner, a rigid beater, means to mount said beater for rotation about an axis, a brush extended on two or more sides of said axis, and means mounting said brush for rotation about its own axis positioned within the orbit described by said beater and for vertical translation to effect adjustment of the covering-contacted lower side of said brush.

17. In a rotary agitator for a suction cleaner, a rigid beater, means to mount said beater for rotation about an axis, a brush extended on two or more sides of said axis, means mounting said brush for rotation about its own axis positioned within the orbit described by said beater and for vertical translation to effect adjustment of the covering-contacted lower side of said brush, and means to transmit a positive rotating force to said brush upon rotation of said beater.

18. In a rotary agitator for a suction cleaner, a rigid beater, means to mount said beater for rotation about an axis, an helical brush extending through substantially 360 degrees circumferentially and having a diameter of the same magnitude as the orbit described by said beater in rotation, means mounting said brush for independent rotation about an axis within the orbit described by said beater and for translation relative to the axis of said beater, and means to space circumferentially said beater and brush.

CHARLES H. TAYLOR.
